UNITED STATES PATENT OFFICE.

BEDFORD HAMMER, OF SANTA ANA, CALIFORNIA, ASSIGNOR OF ONE-THIRD TO JOHN E. BAIRD AND ONE-THIRD TO NOLAN M. DOSS, BOTH OF LOS ALAMITOS, CALIFORNIA.

DISPENSING DEVICE.

Application filed January 30, 1925. Serial No. 5,782.

This invention relates to dispensing devices and more particularly to those adapted to the dispensing of cigarettes, chewing gum, raisins, candy and other commodities commonly wrapped in packages or cartons.

The object of this invention is to provide a dispensing device of the character described which will have the capacity to maintain a substantial supply of various commodities or brands of the same commodity, being provided with selective means to be manually operated for procuring articles from the dispenser.

A further object is to provide in a dispensing device of the above described character a display front having dummy packages indicating the commodity contained in the dispenser and thereby avoiding undue handling or exposure of the articles to be vended.

20 My dispensing device is intended to be operated by storekeepers or authorized persons but not by the general public, except in such places where they may pay for the articles dispensed as the device is not coin operated.

25 A further object is to provide counting devices in the dispensing device so that an accurate account may be kept of the various articles sold therefrom.

30 Referring to the drawing, Fig. 1 is a perspective of the dispensing device as seen when set up for operation.

Fig. 2 is a perspective view of the device showing the door open to disclose the interior construction.

Fig. 3 is a sectional elevation of the dispensing device taken on the line 3-3 of Fig. 1.

40 Fig. 4 is a fragmentary sectional elevation illustrating the operation of the dispensing device.

Fig. 5 is a sectional plan view of the dispensing device taken on the line 5-5 of Fig. 3.

45 Describing the invention, a cabinet 1 provided with a door 2 is mounted upon a platform 3 which is adapted to rest upon any table or counter 4. The cabinet comprises ends 5, a top 6, a back 7 and a front 8. Within this cabinet is a partition 10 disposed parallel to the back 7 and extends from the top 6 to a point 11 a distance

above the platform 3 slightly greater than the thickness of a carton 13 to be dispensed.

50 A series of vertical partitions 12 are spaced laterally within the cabinet and extend from the large partition 10 forward a distance slightly greater than the width of the carton 13 to be dispensed. A lower horizontal panel 9 of the front 8 is disposed above the platform 3 and parallel thereto forming a passageway 15 for the cartons 13 from the interior of the cabinet 1.

The door 2 comprises a frame structure 16 having a glass front 17, a back 18 and a hinged rear panel 19, as shown in Fig. 2. A display card or dummy cartons 34 are inserted in an opening 20 between the glass 17 and the back 18 and the panel 19 is then closed and held shut by a latch 21.

70 The platform 3 is formed of a base 22, a back 23, a front 24 and a top 25. Slots 26 are cut longitudinally in the top 25 for a purpose hereinafter designated.

75 Mounted within the cabinet 1 and adapted to roll upon the platform 3 is a plurality of pushers 27. Each of these has a body 28 the approximate thickness of the carton 13 and is provided with rollers 29 to facilitate its movement. A rod 30 is attached 80 to the front end of the pusher 27 and is bent to extend longitudinally parallel to the base 22 and to project through an opening 31 in the front 24.

85 It will now be seen that the slot 26 permits passage of the rod 30 in a limited reciprocating movement. The rod 30 is normally held in a retracted position by spring 32 as shown in Fig. 3, but upon grasping a button 33 on the outer end of said rod, the rod 30

80 may be drawn forward against the action of the spring 32 bringing with it the pusher 27 which will clear the lower end 11 of the partition 10 and the lower panel 9 of the front 8, as shown in Fig. 4. The forward 95 end of the slot 26 will inhibit further movement of the rod 30 when it has performed the desired function. The purpose of the pusher 27 is to actuate the carton 13 and push one carton at a time from the lower end of the stack of cartons out upon the platform 3. A quick manipulation of the button 33 will bring the carton 13 forward with considerable force which will propel

the said carton out upon the exposed portion of the platform 3.

The rod 30 is formed with an offset 35 adapted to actuate a tappet 36 of a standard counting device 37. The front 24 of the platform 3 is formed with a plurality of openings 38 through which the numerals on the counting device may be seen.

The operation of the dispensing device is as follows: The article or brand which it is desired to purchase is selected by reference to the display cartons in the door 2. The operator then grasps the button 33 on the rod 30 corresponding to the vertical column in which the desired article appears, drawing the rod 30 outwardly thereby ejecting a single carton 13 from the column of cartons within the cabinet 1 by means of the movement of pusher 27. As the pusher 20 moves the lowermost carton outwardly the upper part of the body of the pusher supports the remaining cartons in the column until it has withdrawn to its normal contracted position whereupon the entire column of cartons descends and another carton 25 is in place for ejection. The large partition 10, the small partitions 12 and the back 18 of the door 2 provide a plurality of vertical chambers the approximate size 30 of the cartons thereby retaining them in position. As the rod 30 is moved outwardly for ejecting a carton the offset 35 engages the tappet 36 and actuates the tappet sufficiently to register a number on the counting device 37, thus making it possible to at

any time ascertain the number of sales of any particular commodity or brand of articles being vended.

In my dispensing device the lower horizontal panel 9, is of sufficient height above the platform 3 so that the passageway 15 is always open and the operator may thus readily ascertain if there are packages in any stack and if for any reason the pusher 27 should refuse to operate he may obtain the packages by hand.

Various changes may be made without departing from the spirit of the invention as claimed.

I claim:

A dispensing device, comprising in combination a cabinet having partitions forming receptacles adapted to contain packages to be dispensed, a platform upon which the packages rest and may be received, said platform having a slot below the receptacle, a panel spaced above the platform and leaving a permanent opening the height of the package, a door secured to the cabinet and forming a closure with the panel, a pusher 50 slidably mounted on the platform having a front surface to engage a package resting on the platform and thrust it forward and having an upper surface to support a package and a rod through the slot and 55 connected to the pusher and a spring to retract said rod and pusher.

In testimony whereof I have signed my name to this specification.
